US00D846883S

(12) **United States Design Patent** (10) Patent No.: **US D846,883 S**
(45) Date of Patent: **** Apr. 30, 2019**

(54) **HANDLE OF AN ORAL CARE IMPLEMENT**

(71) Applicant: **Colgate-Palmolive Company**, New York, NY (US)

(72) Inventors: **Brian Bloch**, Hillsborough, NJ (US); **Takahide Okai**, Highland Park, NJ (US); **John Gatzemeyer**, Hillsborough, NJ (US)

(73) Assignee: **Colgate-Palmolive Company**, New York, NY (US)

(**) Term: **15 Years**

(21) Appl. No.: **29/629,213**

(22) Filed: **Dec. 12, 2017**

(51) LOC (11) Cl. **04-02**

(52) U.S. Cl. **D4/101**

(57) **CLAIM**

The ornamental design for a handle of an oral care implement, as shown and described.

DESCRIPTION

FIG. 1 is a front perspective view of a handle of an oral care implement according to the new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
